J. H. Quackenbush,
Harness Knife,
N° 80,765. Patented Aug. 4, 1868.

Inventor;

J. H. Quackenbush

United States Patent Office.

J. H. QUACKENBUSH, OF SPRINGFIELD, MASSACHUSETTS, ASSIGNOR TO HIMSELF AND J. H. RILEY, OF SAME PLACE.

Letters Patent No. 80,765, dated August 4, 1868.

IMPROVEMENT IN HARNESS ROUND KNIFE.

The Schedule referred to in these Letters Patent and making part of the same.

TO ALL WHOM IT MAY CONCERN:

Be it known that I, J. H. QUACKENBUSH, of Springfield, in the county of Hampden, and Commonwealth of Massachusetts, have invented a new and useful Improved Harness Round Knife; and I do hereby declare that the following is a full, clear, and exact description thereof, reference being had to the accompanying drawings, making a part of this specification, and to the letters of reference marked thereon, in which—

Figure 1 is a side view of a knife, with my invention applied.

Figure 2 is another view of the handle and socket, with the blade removed.

The nature of my invention consists in the construction of a harness-maker's round knife, whereby the blade may be made movable in its handle or socket, so that each corner of the blade may be more properly adjusted for certain operations in cutting out different kinds of work than can be done by the use of the ordinary round knife.

It is well known that the ordinary round knife is not particularly adapted to any particular kind of work, unless it is so permanently constructed, and then the constant use of each particular point in doing its peculiar kind of work, wears the point away much faster than would be the case if the blade were adjustable in its handle or socket.

My invention is intended to obviate these objections, as I construct the knife in such manner that the blade can be adjusted at any desired angle with reference to the handle, and is so arranged that one corner of the blade may be used for one kind of work, and, by a different adjustment of the blade in its socket, the other corner of the blade may be used for the same kind of work, so that the corners of the blade will wear or last much longer than when the knife is made in the ordinary manner, and the blade may be set at any desired angle, to suit the operator.

Another advantage of my invention is, that different sizes and shapes of blades may be made for one socket or handle, and, by the use of a proper screw or pivot, when one blade becomes worn or injured from use, it is easily and quickly removed, and another inserted in its place; or, for different kinds of work, different blades may be used in the same handle, making a set of knives much cheaper than a set made in the ordinary manner.

That others skilled in the art may be able to make and use my invention, I will proceed to describe its construction and mode of operation.

In the drawings—

g represents the handle of the knife, into which is inserted the socket *b*, having a longitudinal slot, *i*, made therein.

Through the socket *b*, and perpendicular to the slot *i*, is a hole, *c'*, and near the end of the socket *b* is another hole, having a thread cut therein, into which is fitted the screw *d*, which has a head with a slot cut therein, in which to insert a screw-driver, or other instrument, to turn it, or it may be a thumb-screw, and be turned with the hand.

The blade *A* has a perforation in its shank, *b'*, through which passes the pivot *c*, and at *e* is a curved slot, formed on the arc of a circle, having for its centre the centre of the rivet or pivot *c*, said curved slot *e* being of the proper length, and of a width to admit the insertion of the threaded portion of the screw *d*. The corners, *h l*, of the blade are made quite pointed and sharp, in the usual manner.

f is a ferrule, to preserve the handle, and keep the socket *b* fast therein.

Its operation is as follows:

The blade *A* being secured in the slot *i* of the socket *b*, by means of the pivot *c*, which may be a small screw, if desirable, the screw *d* is inserted in its threaded hole in the socket *b*, and also passing through the curved slot *e* in the blade *A*. If it is desired to use one point, *h*, for cutting out fine work, the blade *A* is turned to one side, as shown in red lines in fig. 1, and the screw *d* is then turned in tightly, which causes both sides of the socket *b* to clasp tightly the sides of the blade *A*, thus holding said blade *A* securely in that position.

If, in cutting, the handle *g* is now held in a horizontal position, with the point *h* downward, a small portion only of the said point *h* enters the leather, which is particularly desirable in certain kinds of work.

On the other hand, if the handle *g* be held in a horizontal position, with the point *l* downward, the said point *l*, with a very considerable portion of the edge of the blade forward of the point *l*, will enter the leather, in the operation of cutting, and this feature is favorable for certain other kinds of work. Then, if it is desired to change points, to prevent rapid and uneven wear, the screw *d* may be slightly loosened, the blade be turned upon its pivot *c* to the other side, or to a corresponding opposite position in its socket, and the screw *d* tightened again. The point *l* may now be used for fine cutting, and the point *h* for other straight or coarse work.

I am aware that a stationary round knife has long been in use, but never, to my knowledge, has such a knife been made adjustable.

Having thus described my invention, what I claim as new, and desire to secure by Letters Patent, is—

The blade *A*, having the curved slot *e* therein, and hung in the slot *i* of the socket *b* by means of the pivot *c*, and secured in position in said slot *i* by means of the screw *d* passing through, or partially through, the socket *b*; and through the curved slot *e*, the whole forming a harness-knife, and constructed and operating substantially as herein described, and for the purposes specified.

J. H. QUACKENBUSH.
